FLOW CONTROL PLUNGER ASSEMBLY
 George Sabaka, R.D. 3, Hanover, Pa.
 Filed Nov. 15, 1963, Ser. No. 324,026
 1 Claim. (Cl. 222—327)

The present invention is broadly concerned with plungers for feeding or expelling material from a container. The present invention is more particularly concerned with a plunger, especially a plunger assembly which is adapted for controlling the flow of viscous, mastic-like or semi-fluid materials such as, for example, a caulking compound from the cartridges or containers in which such materials are sold or dispensed.

Thus, the present invention is more particularly concerned with a caulking gun and cartridge therefor, and relates to a caulking assembly that utilizes a disposable cartridge having a dispensing spout at one end thereof and a piston at the other end thereof.

Caulking guns that employ disposable cartridges are well known in the art and generally comprise a gun which supports the cartridge and which is provided with a lever actuated plunger that is adapted to engage and move the cartridge piston of the disposable cartridge toward the spout. Thus, movement of the cartridge piston exerts pressure on the caulking material within the cartridge and displaces the caulking material through the dispensing spout of the cartridge. However, an annoying problem encountered with this type of caulking assembly is that, when the assembly is set aside after use or between uses, the caulking material remaining in the cartridge expands and thus oozes or drips from the spout. This is evidently due to the relatively high compressibility and relatively slow recovery of the caulking material. It might also be due to some extent, especially with a paper cartridge, to a slight swelling of the cartridge body. The expansion of the caulking material, during use, from the spout builds up pressure in the cartridge with resulting compression of the material which, unless permitted to expand within the cartridge, will subsequently expand through the spout. This is particularly annoying since, when the gun is set aside, the caulking material or compound which remains in the cartridge oozes and drips on the table or other support upon which it is placed, creating an untidy and undesirable situation.

Various expedients have been used heretofore to prevent the caulking compound or other semi-fluid material from thus oozing or dripping from the spout. For instance, the use of a flexible diaphragm among other things have been proposed. However, none of these have proven satisfactory since the diaphragm has a tendency to adhere to the compound and cannot overcome this adherence sufficiently or quickly enough to prevent the oozing or loss of compound from the dispensing spout. Moreover, in all cases where such a diaphragm has been employed, no provision has been made for the release of the air which is confined between the diaphragm and the caulking compound so that it becomes extremely difficult to actuate the diaphragm with any degree of efficiency.

The present invention is concerned with a unique caulking assembly whereby positive control can be exerted on the remaining material within the caulking gun when it is not in use to positively control and prevent the flow or seepage of material from the gun. The present invention in particular comprises an integrated assembly comprising the plunger of the gun and the movable piston element of the disposable cartridge.

In essence, the piston element movable within the cartridge is a cuplike cylindrical element, the diameter of which is substantially equivalent to the inner diameter of the disposable cartridge, having sufficient tolerance to

2

permit the piston to move within and through the cartridge and to substantially prevent any leakage of the compound behind the piston. The piston has a circumferential skirt element extending rearwardly substantially vertical from about the circumference of the base. The distance that the skirt element of the piston extends from the base element of the piston may vary appreciably, but is generally in the range from about $\frac{1}{4}$ " to $\frac{5}{8}$ " to $\frac{3}{4}$ ".

5 The distance the skirt element extends rearwardly from the base of the piston may be varied depending upon related conditions such as upon the diameter of the base.

In accordance with the present invention, ears or lugs or projections extend inwardly from the skirt element of the piston. These may be attached by any means desirable, but are preferably punched lugs or ears which are secured by punching from the outer surface of the skirt element of the piston. These extending projections which extend inwardly from the skirt element are sufficiently distant from the flat surface of the base of the piston so 10 as to permit engagement of the plunger of the gun as hereinafter described. Generally it is preferred that these projections be from $\frac{1}{16}$ " to $\frac{1}{8}$ " to $\frac{1}{4}$ " distant or away from the flat surface of the base element of the piston.

15 As pointed out heretofore, the gun is substantially a conventional one wherein the piston of a cartridge is caused to move through the cartridge by a plunger element of the gun which is actuated by a lever and a ratchet assembly. Any type of ratchet assembly may be used as, for example, one described in U.S. Patent 2,889,085 20 issued June 2, 1959; inventor: H. B. Collins; entitled "Drive Means for Caulking Gun Plungers."

In accordance with the present invention, the plunger element of the gun is actuated by the ratchet assembly of the gun. This plunger element is a disclike metallic

25 element and contains a number of cuts around the periphery thereof which are of a dimension or depth to permit the disclike plunger to pass by the projections of the piston skirt and to seat securely on the base of the piston. Orientation to permit this passage can be secured by rotating 30 the cylindrical dispensable cartridge to the desired spot or alignment of the projections with the cuts or indentations. When it is desired that no further caulking is necessary, the handle controlling the plunger rod is rotated disengaging the notches from the ratchet or

35 plunger rod and, at the same time, moving the non-indent portion of the plunger edges behind the protruding ears of the piston. A backward thrust can then be exerted on the handle, pulling back the plunger and the piston from the nozzle, thereby creating a positive thrust 40 of air in a negative direction through the nozzle and thereby actually causing the mastic or caulking compound to move backwardly within the cartridge itself.

The apparatus assembly of the present invention may 45 be particularly understood by reference to the drawings illustrating one embodiment of the same. FIGURE 1 shows the gun and the cartridge, and the cartridge piston and gun plunger within the cartridge in a nonengaged position. FIGURE 2 shows the gun plunger and cartridge piston in a locked or engaged position whereby as 50 a rearward thrust is exerted on the handle a rearward thrust will be exerted on the piston by the plunger causing the piston to move away from the cartridge nozzle.

55 Referring specifically to the drawing, a caulking gun 1 is shown having disposed therein a dispensable cartridge 2 having a dispensing nozzle or equivalent means 3 at the front end thereof. The cartridge 3 is positioned in caulking gun 1 in a conventional manner; namely, by thrusting the same rearwardly within housing 4 of gun 1 and then permitting the nozzle 3 to seat in slot 5 and to be locked therein by housing 6 of the caulking gun. Movable piston element 7 comprising a piston base 8 and a

backwardly extending piston skirt 9 is shown approximately halfway through the disposable caulking cylinder 2 or container 2. Punched inwardly from piston skirt 9 of the piston 7 are projections 10 which are a distance above or away from piston base 8. The gun plunger element or disc 11 is actuated by means of plunger rod 14 having notches 12 and a ratchet assembly 13, in conjunction with lever 21 (not shown in detail), within handle 1. Plunger or disc 14 is shown disposed a distance apart from the piston 7 in a nonengaged position. Plunger 11 contains a number of peripheral notches 15 or indentations which will permit the placing of plunger 11 on piston base element 8 of piston 7 by permitting protrusions or projections 10 to pass through the notches 11.

When it is no longer desired to utilize the gun, gun or plunger rod 14 is rotated by means of handle 20 approximately 180°. This places the slots 15 in nonalignment with the ratchet in the handle. This rotative movement disengages notches 12 of gun or plunger rod 14 from the ratchet assembly and permits free movement of the plunger rod backwardly since it is not engaged in the ratchet assembly.

The rotative movement, as pointed out, also places slots 15 of the disc or plunger 11 in nonaxial alignment with projections 10 of piston skirt 9, thereby placing projections 10 in direct contact with the back surface of plunger 11.

Upon exerting a backward thrust on handle 20, plunger rod 14 will move freely to the rear, causing plunger 11 to move to the rear and also causing piston 7 to move toward the rear by means of the thrust exerted by the back surface of plunger 11 on the projections 10 of skirt 9. This positive effort and thrust will cause air to backflow through nozzle 3, thereby clearing this nozzle of the mastic or caulking compound and causing the same to move into the main body of the cylinder.

This has two extremely desirable features. In the first place, it prevents oozing and seeping of the mastic material or caulking compound, and also effectively clears nozzle 3 of caulking compound and mastic material. As is well known in the art, the retention of a relatively small amount of caulking compound in a narrow area such as a nozzle 3 causes this material to harden and, in many instances, makes it extremely difficult to use the cartridge subsequently.

The number of projections and slots on the piston and plunger may be varied appreciably, depending upon the other features of the assembly. However, it is preferred that the notches and slots approximate from about 2 to 6, preferably about 3. The extent to which the projections are extended within the skirts of the piston may be also varied appreciably. They should be of sufficient length so as to have the necessary mechanical strength to avoid shearing of the same upon exerting a backward thrust upon the piece which is interlocked. FIGURE 2, as pointed out heretofore, shows the plunger 11 engaged in piston 7 be-

hind projections 10 of the piston skirt. It is to be noted that rotation of handle 20 approximately 180° disengages the notches of the plunger rod from the ratchet and, at the same time, rotates plunger 11 in a manner to seat and engage the plunger in the piston behind the projections 10.

Thus, the present invention is generally concerned with an improved caulking gun or equivalent assembly which prevents seepage or leakage of the material from the container when not in use. As pointed out heretofore, the present assembly may be used for feeding or expelling materials from any type of container wherein, during the expulsion, a pressure is exerted on the mastic material and which, if not relieved, will cause the material to seep or ooze from the gun when not in use. The invention will also, as pointed out heretofore, completely free the narrow nozzle of the material when not in use, thereby preventing hardening of the material and subsequent choking of the nozzle.

What is claimed is:

20 An assembly which comprises in combination, a disposable cylindrical cartridge containing a viscous material, having a spout at one end and an axially movable piston element at the other end; and a gun which supports the cartridge provided with an axial movable plunger and including a plunger rod containing indentations about part of its circumference for meshing with means for incrementally advancing said plunger rod and said plunger, said piston element being characterized by having a piston base and a circumferentially backwardly extending piston skirt, said piston skirt containing projections and perforations both formed by portions of the skirt being punched with said projections extending inwardly from said piston skirt distant from said piston base, said plunger being characterized by containing a number of indentations about its periphery so as to permit said plunger to pass by said projections and bear against said piston base, means for rotating said plunger and said plunger rod so as to secure a nonalignment between said indentations and said projections and to secure a demeshing of the indentations of the plunger rod from said means for incrementally advancing said plunger rod and said plunger, whereby as said plunger is withdrawn rearwardly, said projections bear against the top surface of said plunger causing said piston element to move rearwardly within said cartridge and causing air to backflow through said spout.
